(57) **CLAIM**

The ornamental design for a medicated cream and ointment dispenser with a ruled piston, as shown and described.

DESCRIPTION

FIG. 1 is a perspective view of a medicated cream and ointment dispenser with a ruled piston showing my new design;

FIG. 2 is a top view thereof;

FIG. 3 is a bottom view thereof;

FIG. 4 is a front elevational view thereof with the rear elevational view being a mirror image thereof; and,

FIG. 5 is a right side elevational view with the left side being a mirror image thereof.
